UNITED STATES PATENT OFFICE.

JEREMIAH WILLIAMS, OF ABERGELE, AND LLEWELLYN THOMAS JONES, OF OLD COLWYN, WALES.

ATTACHMENT FOR RESERVOIR-PENS.

1,282,511.

Specification of Letters Patent.

Patented Oct. 22, 1918.

Application filed April 18, 1918. Serial No. 229,425.

To all whom it may concern:

Be it known that we, JEREMIAH WILLIAMS and LLEWELLYN THOMAS JONES, subjects of the King of Great Britain, residing at Abergele, North Wales, in the Kingdom of Great Britain, and Old Colwyn, North Wales, aforesaid, respectively, have invented certain new and useful Improvements in Attachments for Reservoir-Pens, of which the following is a specification.

This invention has for its object to combine with a reservoir pen or with a reservoir pen clip, a receptacle for holding a supply of tablets of ink of the kind that are dissolved in water in the reservoirs of such pens to supply the necessary writing fluid.

According to the present invention, a suitable receptacle for holding a supply of ink tablets is provided, having means for permanently or removably attaching the same directly to the side of the body or cap of a fountain, stylographic or other reservoir pen. In one case the receptacle is so attached directly to the cap or body of the pen at the side, or to a clip or clips which hold the pen sufficiently tightly to prevent accidental detachment, that the material of the pocket can be clamped between the receptacle and the pen, whereby the said receptacle forms the two-fold function of a clamp for holding a pen in the pocket of the owner's apparel, and a holder for the ink tablets. In another case such receptacle performs the single function of a holder for ink tablets, the clip being relied upon to perform the function of holding the pen in the wearer's pocket.

In the accompanying drawings:—

Figures 1, 2 and 4 are perspective views of our reservoir pen attachment in which the receptacle performs the two-fold function aforesaid, and

Figs. 3 and 5 are perspective views of our reservoir pen attachment in which the receptacle performs the single function of a holder for ink tablets, the clip being relied on for holding the pen in the wearer's pocket.

Referring to these drawings, A is the box or receptacle for holding a supply of ink tablets, and B the cap or lid for closing the same, or a cover, or half covers moving in opposite directions, or a sliding lid may be provided instead. This box or receptacle is provided with means for permanently or

removably attaching it to the body or cap of a reservoir pen such as C at the side in such manner that the two elements A and C are spaced away from each other such a distance that the material of the pocket can be clamped between them.

In Fig. 1 the box or receptacle A is made straight longitudinally but is of curved or segmental-circular shape in cross section, and has attached to its concave face a pair of spring clips such as D (which partially or wholly encircle the pen when inserted thereinto) and is also provided with abutments E against which the pen abuts, and which keep the box or receptacle spaced away from the pen such a distance that the material of the pocket can be clamped between the lower part of the receptacle and the pen. The clips D which clamp the pen sufficiently tightly to prevent the accidental detachment of the pen, act as springs to pull the box or receptacle with the abutments E against the outside of the pocket, and thus the said receptacle performs the double function of a clip for holding the pen in the pocket and as a holder for the ink tablets. The pen can be inserted longitudinally into the clips D. The surface of the lower part of the receptacle A which comes against the pocket may be roughened or serrated, or it may be rubber lined to grip the front of the pocket.

In Fig. 2, the receptacle A is shown cylindrical and has attached to it a spring clip D, and when a pen is inserted into this clip, the receptacle is held spaced away from the pen, so that the material of the pocket can be clamped between the lower part of the receptacle and the pen thus acting as a clip.

In Fig. 4 the arrangement is similar except that the receptacle A is made of a different shape in cross section and is provided with a sliding door F instead of the screw-on cap G of Fig. 2. In Fig. 3 the clip D which is attached to the receptacle A has a horn like extension H depending downward below the bottom of the receptacle A between which horn-like extensions and the pen the material of the pocket is clamped. The lower end of this extension has a projecting nose piece I which serves to grip or bite the material of the pocket. In this example the receptacle A is not relied on to grip the pocket, and can consequently be made shorter in length. In all these figures the

boxes or receptacles A are permanently secured to the clips D by riveting or by other suitable connection, the clips forming the means by which the receptacle A is removable held against the side of the pen. If desired however the receptacle A of Figs. 1, 2, 3 and 4 may be permanently secured direct to the side of the pen and parallel thereto in such manner as to be spaced away from the pen a sufficient distance as to enable the material of the pocket to be clamped between them.

In Fig. 5 the clip D is also provided with a horn-like extension depending downward but this extension J is formed with clipping tongues K projecting the reverse way to the clipping tongue D, the tongue D being adapted to clip the pen, and the tongues K being adapted to clip the receptacle A, while the material of the pocket is clamped between the pen C and the elastic horn-like extension J. In this case therefore the receptacle A is readily detachable from the clip instead of being riveted or otherwise permanently secured thereto. L is a small shoulder or abutment for the bottom of the receptacle A to rest on, so as to prevent it falling out of the clips accidentally, and M a small nose piece to bite into the material of the pocket.

The features of the invention will now be apparent. It is to be understood however that we do not consider ourselves limited to the precise details of construction herein described, as changes could be readily suggested, which while they might change the appearance of the attachment would not involve a departure from the scope of the invention herein set forth. Accordingly the receptacle A can be of any other suitable shapes than those illustrated, and any other suitable form of clip or ferrule may be employed. Furthermore the receptacle may be attached to one clip or to two or even more clips as may be desired.

We declare that what we claim is:—

1. A device of the kind described for use in connection with reservoir pens, comprising a receptacle for holding ink tablets, a cap or slide for closing the same, and means for attaching the receptacle to the body or cap of the pen at the side.
2. A device of the kind described for use in connection with reservoir pens, comprising a receptacle for holding ink tablets, and means for attaching the receptacle to the

body or cap of a reservoir pen at the side and parallel thereto in such manner that the two elements are spaced away from each other such a distance that the material of the wearer's pocket can be clamped between them.

3. A device of the kind described for use in combination with reservoir pens, comprising a receptacle for holding ink tablets, a clip or clips secured thereto for receiving and holding a reservoir pen in a removable manner so that the receptacle shall be located at the side of the pen, and means for holding the receptacle spaced away from the pen so that the material of the pocket can be clamped between them.

4. In a device of the kind described for use in combination with reservoir pens, comprising a receptacle for holding ink tablets and a clip or clips secured thereto at the side for receiving and holding the reservoir pen in a removable manner, a horn-like extension depending downward below the bottom of the receptacle between which extension and the pen the material of the pocket is clamped.

5. A device of the kind described for use in combination with reservoir pens, a receptacle for holding ink tablets, a horn-like spring member having a clip or clips projecting therefrom in one direction for holding a reservoir pen, and clips projecting in the reverse direction for holding the receptacle, the horn-like extension being spaced away from the pen so that the material of the pocket can be clamped between them.

6. A device of the kind described for use in combination with reservoir pens, comprising a receptacle for holding ink tablets, a clip or clips secured thereto at the side for receiving or holding a reservoir pen in a removable manner, a horn-like extension depending downward from the clip so as to project below the receptacle, and a projection or stop at the bottom to bite into the material of the pocket.

In witness whereof, we have hereunto signed our names this 28th day of March 1918, in the presence of two subscribing witnesses.

JEREMIAH WILLIAMS.
LLEWELLYN THOMAS JONES.
